SHINGLE

Frederick C. Young, Westport, Conn.

Application May 9, 1936, Serial No. 78,741

5 Claims. (Cl. 108—7)

This invention relates to new and useful improvements in coverings for roofs and sidings and has particular relation to an improved shingle for these coverings.

5 An object of the invention is to provide an individual type shingle of such construction that in a roof or siding covering, wherein the shingles are wide spaced, the appearance is that obtained when thick butt shingles are used.

10 Another object is to provide a shingle in which the lower edge is sealed to prevent bleeding and drying out of the asphalt or saturant.

15 A further object is to provide a shingle including means whereby the exposed edge portions of the shingles, when applied to a roof or siding, are held in place in flat condition whereby the wind is prevented from getting under them to raise them and blow them off the roof or siding.

20 Other objects and advantages will become apparent from a consideration of the following detailed description taken in connection with the accompanying drawing wherein satisfactory embodiments of the invention are shown. However, it is to be understood that the invention is not limited to the details disclosed but includes 25 all such variations and modifications as fall within the spirit of the invention and the scope of the appended claims.

In the drawing:

30 Fig. 1 is an elevational view showing a number of the improved shingles as applied;

Fig. 2 is an enlarged sectional view taken substantially along the plane of the line 2—2 in Fig. 1;

35 Fig. 3 is a similar view taken substantially along the plane of the line 3—3 in Fig. 1;

Fig. 4 is a plan view on a somewhat smaller scale showing the under side of the lower portion of the improved shingle;

40 Fig. 5 is a plan view showing the outer side of the lower end portion of the shingle;

Fig. 6 is an edge view of the portion of shingle shown in Fig. 4;

45 Fig. 7 is a similar view but on a much larger scale;

Fig. 8 is an end elevational view taken as though looking from the lower edge of Fig. 5; and

Fig. 9 is a view similar to Fig. 8 but showing a slightly modified arrangement.

50 Referring in detail to the drawing the improved shingle as here disclosed comprises a body 18 including a fibre base, preferably of felt or the like impregnated with a suitable saturant such for example as asphalt or the like, whereby the body is waterproof and has a certain amount

of flexibility so as not to be brittle or readily breakable. On the upper or outer surface of the body there is a covering 11 of granular mineral material such for example as crushed slate or other suitable material. The shingle may be 5 made up in the usual sizes and weights following the established practice.

At one end the corners of the shingle are cut away providing shoulders 12 at opposite ends of a flange-like extension 13 (see the dotted lines 10

Fig. 4) and thereafter such extension is folded under the body of the shingle providing an underfolded flange 14. This folding is done while the shingle is warm so that it is sufficiently soft or pliable to be folded without breaking. This 15

flange being an extension of the main body of the shingle also has its outer surface covered with the granular material 11 so that the end edge portion 10a of the shingle between the shoulders 12 and represented by the underfolded 20

flange 14 is of the same color and finish as the outer surface of the shingle. The underfolded flange 14 is secured to the under surface of the 25

body of the shingle by any suitable cementing material 28, preferably some such material as asphalt. It will be seen from Fig. 1 that the 30

underfolded portion 14 is of considerably less length than the length of the butt of the shingle, that is the exposed portion between the lower edge of the shingle and the lower edges of the 35

shingles in the next higher row. Thus the remainder of the body portion of the shingle is not stiffened up by the folded portion but is left flexible so that it may seek its own level when warmed by the heat of the sun.

The underfolded flange 14 may be used to secure in place a locking strip 15 the main portion of which is located in the fold but the end portions of which extend beyond the ends of the 40

fold forming extensions 16 offset as at 17 and adapted to be used for the purpose of anchoring the lower end of the shingle to the next lower shingles for securing the ends of the shingle in a flat condition so as to prevent the wind entering 45

under and lifting them. A strip or quantity of asphalt or similar material 18 may be carried by the underside of the shingle at the free edge of the flange 14. Strip 15 is of metal and while it may be a piece of round wire it is preferred 50

that it be of flat stock so that it will not be likely to turn about its longitudinal axis and get out of position and thus interfere with the rapid applying of the shingles as will later be fully set forth.

With the shingle described there is a distinct 55

gain in appearance when the shingles are applied by the wide spaced method. Such method calls for the laying of one shingle over two widely spaced shingles. Figs. 1, 2, and 3 show the manner in which the shingle of the invention is applied. To cover a surface shingles A and B are applied in parallel relation with their opposed side edges 19 and 20 in spaced relation. Next shingle C is applied in position with its side edges 21 and 22 overlying the edges 19 and 20 of the shingles A and B and with the opposed edges of such shingles A and B abutting the ends of the underfolded flange 14 of the shingle C. In applying shingle C the extensions 16 of its metal strip 15 are inserted under the opposing edge portions of the pair of shingles A and B so that the lower edge portion of shingle C is secured and anchored in a flat condition. Also the asphalt strip 18 on the under surface of each shingle causes it to stick or adhere to the next lowermost shingle further anchoring the lower exposed end portion of the shingle.

The lower end or edge 24 of shingle C is above the lower ends or edges of shingles A and B, being over the upper end portion of a previously laid shingle D. Therefore the upper end 25 of shingle C is above or higher up the roof or siding than the ends 26 and 27 of shingles A and B. Thus the shingles in the adjacent vertical rows are staggered, while the adjacent shingles in horizontal rows are quite widely spaced, this spacing being determined by the length of the underfolded portion 14. Following the application of shingle C the shingles E and F are applied in parallel spaced relation overlapping the side edges of the shingle C in such manner that the ends of their underfolded portions 14 are abutting the edges of such shingle C and that the extensions 16 of their metal strips 15 project under the overlapped edges of shingle C. Thereafter shingle G is applied in the manner described when considering the application of shingle C and the operation is repeated until the roof or siding is covered.

In each case the underfolded flange or portion 14 of a shingle fills the space between the opposed edges of the next lowermost shingles. Also the lower edge of each shingle is anchored by its metal strip and by the asphalt strip 18. However in some instances the metal strip may be omitted and the asphalt strip used alone to anchor the shingle or secure it in flat condition, and in other instances the metal strip may be used alone, the asphalt strip being omitted.

Attention is particularly called to the fact that since the underfolded portion 14 in each shingle is formed from an extension of the body of the shingle, the outer surface of such portion 14 and the curved connecting edge portion 10a are covered with the granules of slate or the like. Therefore the butt end portion of each shingle between the next laterally adjacent shingles is the same in appearance as the other outer surface portions of the shingle. There is no contrast in color or otherwise.

Owing to the fold the applied shingles give the heavy butt or shadow effect desired, greatly improving the appearance of the covering. The shingle is protected by the fold against the bleeding and drying out of the asphalt that would occur if the lower cut edge of the shingle were exposed. In other words, the lower edge instead of being open and exposed is sealed by this fold. This is important as preserving the shingle and increasing the life of the covering. The impregnation of the shingles with asphalt may be suffi-

cient to secure the fold 14 to the body of the shingle, but ordinarily some additional asphalt is used to secure the fold in place as suggested at 28 in Figs. 3 and 7.

In Fig. 9 the metal strip 15 extending the length of fold 14 is omitted and two similar short pieces 29 are substituted. Such pieces 29 are the same as the end portions of strip 15 and each includes a portion 30 secured by the fold 14 and an offset extension 31 to be disposed under the next adjacent shingles in covering a roof or siding. These may be applied when the fold is made or can be inserted by the workman on the job.

Having thus set forth the nature of my invention, what I claim is:

1. An individual shingle comprising a rectangular body of flexible felt impregnated with asphaltic material and having a continuous butt end, said body having at its lower or butt edge an integral underfolded extension of less width than the width of the shingle and of considerably less length than the butt of the shingle so that the remainder of the shingle is flexible and may seek its own level over an uneven roof surface under action of the sun, said extension being folded under the body while the body is warm and pliable and sealed to the underside of the body by asphaltic material so that the folded edge of the shingle is sealed against bleeding, the top surface of the shingle and undersurface of the folded under extension being covered with granular mineral material and the remainder of the undersurface of the body being free of said granular material.

2. An individual shingle comprising a rectangular body of flexible felt impregnated with asphaltic material and having a continuous butt end, said body having at its lower or butt edge an integral underfolded extension of less width than the width of the shingle and of considerably less length than the butt of the shingle so that the remainder of the shingle is flexible and may seek its own level over an uneven roof surface under action of the sun, said extension being folded under the body while the body is warm and pliable and sealed to the underside of the body by asphaltic material so that the folded edge of the shingle is sealed against bleeding, a transversely extending strip of asphaltic material on the undersurface of the body at the inner free edge of the underfolded portion to seal to the surface of an under-element, the top surface of the shingle and undersurface of the folded under extension being covered with granular material and the remainder of the undersurface of the body being free of said granular material.

3. An individual shingle comprising a rectangular body of flexible felt impregnated with asphaltic material and having a continuous butt end, said body having at its lower or butt edge an integral underfolded extension of considerably less length than the butt of the shingle so that the remainder of the shingle is flexible and may seek its own level over an uneven roof surface under action of the sun, said extension being folded under the body while the body is warm and pliable and sealed to the underside of the body by asphaltic material so that the folded edge of the shingle is sealed against bleeding, a transversely extending strip of asphaltic material on the undersurface of the body at the inner free edge of the underfolded portion to seal to the surface of an under-element, the top surface of the shingle and undersurface of the folded under extension being covered with granular material and the remainder of the undersurface of the body being free of said granular material.

the shingle and undersurface of the folded under extension being covered with granular material and the remainder of the undersurface of the body being free of said granular material.

5. 4. A roof or siding covering composed of individual shingles laid in wide spaced relation in overlapping courses, each shingle comprising a rectangular body of flexible felt impregnated with asphaltic material and having a continuous butt 10 end, said body having at its lower or butt edge an integral underfolded short portion of a width equal to the space between individual shingles in the same course and of considerably less length than the butt of the shingle so that the remainder 15 of the shingle is flexible and may seek its own level over an uneven roof surface under action of

the sun, said under portion being folded under the body while the body is warm and pliable and sealed to the underside of the body by asphaltic material so that the folded edge of the shingle is sealed against bleeding, the top surface of the shingle and the undersurface of the folded under portion being covered with granular mineral material and the remainder of the undersurface of the body being free of said granular material. 5

5. The roof or siding covering of claim 4 in 10 which there is a transversely extending strip of asphaltic material on the undersurface of the body of each shingle at the inner free edge of the underfolded portion to seal to the surface of an under-element. 15
